UNITED STATES PATENT OFFICE.

WILLIAM B. HALL, OF CHICAGO, ILLINOIS, ASSIGNOR TO UNION RAILWAY EQUIPMENT CO., A CORPORATION OF ILLINOIS.

REFRIGERATOR-CAR.

1,290,548.

Specification of Letters Patent. Patented Jan. 7, 1919.

Application filed November 2, 1915. Serial No. 59,202.

To all whom it may concern:

Be it known that I, WILLIAM B. HALL, a citizen of the United States, and resident of Chicago, county of Cook, and State of Illinois, have invented certain new and useful Improvements in Refrigerator-Cars, of which the following is a specification and which are illustrated in the accompanying drawings, forming a part thereof.

10 The invention relates to refrigerator cars and more particularly to those in which the refrigeration of the lading is accompanied by the use of ice and salt. Such cars are commonly provided with tanks for containing the refrigerating mixture and while provision is to be made for the discharge of the brine from time to time, it is desirable that the brine shall be confined while the car is *en route*, as its discharge upon the right of way is to be avoided. Under these circumstances the drainage of the tanks is preferably to be accomplished only in connection with the icing of the cars. It is therefore important that provision be made for discharging the brine as rapidly as possible and that the means provided therefor should be easily operable to provide a free discharge when open and a tight seal when closed. Difficulty has heretofore been experienced in this respect owing to the formation of frost upon the outside of the operative parts and the accumulation of sediment within the tanks and passages. The object of the invention is accordingly to provide a quick opening valve for brine tank refrigerator cars which shall be operable with certainty under all conditions and not subject to injury or deterioration in service.

In the accompanying drawings,

40 Figure 1 is a detail plan view of a refrigerator car embodying the features of improvement provided by the invention, the hatchway cover and the plug for closing the filling opening to one pair of tanks being removed.

Fig. 2 is a sectional view taken on the line 2—2 of Fig. 1, the tanks being shown partly in elevation.

Fig. 3 is similar to a detail of Fig. 2, but 50 shows a modified form of construction.

Fig. 4 is an enlarged side view of the valve with the adjacent parts of the side walls of the tanks shown in section, and

Fig. 5 shows the valve and its operating

means, the valve being shown in section on 55 the plane indicated by the line 5—5 on Fig. 4, and the operating means being shown in elevation.

The brine tanks, as 10, 11, 12 and 13 may be arranged in the end of the car as usual. 60 A detail of the car roof is shown at 14, the side walls of the car at 15, 16 and its floor at 17. All of the tanks at one end of the car communicate with the usual hatchway, generally designated 18. This hatchway 65 may have a central partition 19 and the tanks are preferably arranged in pairs located upon opposite sides of the partition, the filling of the two tanks, as 10, 11 and 12, 13 of each pair being accomplished upon the 70 removal of a plug as 20, which fits the corresponding part of the hatchway opening. The tanks are supported from below by resting upon a skeleton frame 21 which extends between the side walls 15, 16, of the 75 car, a short distance above the floor 17. The tops of the tanks fit the hatchway opening and are additionally supported by partition beams 39, one of which extends across the opening between the two tanks of each pair. 80

In the arrangement illustrated in Figs. 1, 2, 4 and 5, the discharge of brine from the two tanks 10, 11 and 12, 13 of each pair is through a connecting pipe or union 22. This union may be located in any desired position with reference to the height of the tanks but is preferably positioned to extend between the adjacent side walls, as 23, 24, of the tanks a short distance above the supporting frame 21. In this form of construction, 90 each union 22 communicates directly with the interior of both tanks, as 10, 11, of the corresponding pair and is firmly supported by each of said tanks. As shown the union 22 is provided with threaded ends 25 and 26 which project through openings in the side walls 23 and 24, respectively, and clamping nuts, as 27, are applied to the threaded ends 25 and 26 from the inside of the tanks to coöperate with flanges, as 33, which are 95 formed upon the union to abut against said side walls upon the outside.

Each union 22 has a relatively large drain opening 29 intermediate its ends. This drain opening preferably faces downwardly between the adjacent tanks and is controlled by a swinging valve plate 28. To insure against leakage when the valve plate 28 is raised,

a gasket 30 is preferably provided. The gasket 30 is conveniently held in place by having its rim seated in an inwardly facing annular groove 31 formed in that part of the wall of 5 the union 22 which surrounds the mouth of the opening 29. To provide a hinge support for the valve plate 28 which permits of the parts being readily assembled, the valve plate is formed with a hook 32 at one end 10 and the adjacent flange, 33, of the union 22 is formed with a pair of bracket lugs 34 between which an arbor 35 is integrally extended for engagement with said hook 32.

The free end of the valve plate 28 is 15 pivotally connected with a yoke 36. The arms of this yoke straddle the union 22 and the upper end of the yoke is attached to a valve rod 37, which extends upwardly therefrom between the tanks, as 10, 11, and 20 through a slotted opening 38 in the beam 39, for connection with an operating lever 40, as at 42. The lever 40 is preferably so mounted upon the beam 39 as not to project over the tank, as 10 or 11, at either 25 side of the partition to interfere with the icing. It may also serve to prevent the application of the plug 20, when the valve plate 28 is lowered. When so arranged, the raising of the valve plate before the car 30 is permitted to proceed from the icing station is insured. As shown, an apertured bracket plate 41 is mounted upon the beam 39 to surround the slotted opening 38. This bracket plate carries the lever 40, the pivotal connection, as 43, of the lever with the plate being transverse to the beam 39 for causing the lever to swing in a plane which is parallel with the length of the beam. Preferably the relative arrangement of the 40 points of pivotal connection, as 42 and 43 of the lever 40 with the valve rod 37 and with the bracket plate 41 is such that the parts form a toggle for the lifting of the valve plate 28 against the gasket 30 upon 45 the swinging of the lever to the horizontal position illustrated in Fig. 5. The valve plate 28 is thereby forcibly held to its seat and the lever 40 is so positioned as to permit the insertion of the plug 20. On the other 50 hand, the lever 40, occupies the upright position illustrated at the left hand side of Fig. 2 when the valve plate 28 is lowered to permit the drainage of the tanks through the opening 29.

55 In the arrangement illustrated in Fig. 3, all of the tanks, as 44, 45, 46 and 47 at one end of the car are connected for drainage through a single union 48 which is in direct communication with the interior of 60 only one of the tanks, as 44. As shown, each two adjacent tanks are connected at the bottom by a section of hose 49. The parts may be constructed otherwise exactly as illustrated in Figs. 1, 2, 4 and 5, except that 65 the union 48 is provided with a flange 51

at one end which is riveted against the side wall of the adjacent tank, as 45, without communicating with the interior of said tank. In either form of construction a free discharge of the brine is provided when 70 the valve plate, as 28 is lowered, and this valve plate may be quickly moved between the open and closed positions while the operation is not likely to be interfered with by 75 corrosion or accumulations of frost or sediment.

I claim as my invention,—

1. In combination, a car body having an opening in its roof, a horizontal partition beam extending across such opening, a pair 80 of upright tanks located side by side within the car body, the tops of the tanks communicating with the roof opening at opposite sides of the said beam, a pipe supported by and connecting the two tanks below the beam, such pipe having a downwardly facing opening intermediate its ends, a lever pivotally mounted upon the upper side of the beam to swing in a vertical plane which is parallel with the length of the beam, a 90 vertically movable valve plate controlling the said opening in the pipe, and connection between the valve plate and the lever.

2. In combination, a car body having an opening in its roof, a horizontal partition beam extending across such opening, a pair of upright tanks located side by side within the car body, the tops of the tanks communicating with the roof opening at opposite sides of the said beam, a pipe having its opposite ends secured against the adjacent side walls of the two tanks below the beam, the said side wall of one of the tanks being apertured in line with the said pipe and the said pipe being provided with a downwardly 100 facing discharge opening between the tanks, a valve plate hinged to the wall of the pipe at one side of its said discharge opening, a yoke straddling the pipe and having its lower end pivotally connected with the free 105 edge of the said valve plate, a lever pivotally mounted upon the upper side of the said beam to swing in a vertical plane which is parallel with the length of the beam, and a rod extending between the yoke and the 110 lever, the point of connection of the rod with the lever being so disposed with reference to the lever pivot that the lever occupies a horizontal position upon the beam when the valve plate is raised to close the discharge opening in the said pipe and in upright position above the beam when the valve plate is lowered.

3. In combination, a car body having an opening in its roof, an upright tank within the car body, the top of the tank communicating with the roof opening, a lever pivotally mounted within the car roof at one side of the tank to swing in a vertical plane 125 outside of the tank, a drain cock in the side 120

of the tank below the roof and an operating rod extending between the drain cock and the lever.

4. In combination, a car body having an opening in its roof and a cover for such opening, a tank located below the opening and having a valve-controlled drain outlet,

a lever for controlling the valve of the outlet, such lever being pivoted within the opening and arranged to swing upwardly there-through in opening the valve and to swing downwardly thereinto in closing the valve. 10

WILLIAM B. HALL.
